UNITED STATES PATENT OFFICE.

HENRIETTA GERWIG, OF ALLEGHENY, PENNSYLVANIA.

DESIGN FOR A DUST-PAN.

SPECIFICATION forming part of Design No. 31,183, dated July 11, 1899.

Application filed June 16, 1899. Serial No. 720,858. Term of patent 14 years.

To all whom it may concern:

Be it known that I, HENRIETTA GERWIG, a citizen of the United States of America, residing at Allegheny, in the county of Allegheny and State of Pennsylvania, have invented a certain new and useful Design in Sweeping-Pans, of which the following is a specification, reference being had therein to the accompanying drawings.

10 This invention relates to certain new and novel designs in dust-pans.

The invention consists of a new form and the outer contour lines of a pan.

In the drawings, Figure 1 is a view in perspective of my improved dust-pan. Fig. 2 is a top plan view of the same. Fig. 3 is a vertical sectional view taken on the line 3 3 of Fig. 2.

Referring to the drawings by reference-numerals, 1 indicates the sides of the pan, which

are curvilinear in form. Said sides in plan view will taper outwardly.

The reference-numeral 2 indicates the base or body portion of the pan, the rear of said body portion being semicircular in form, as shown at 3, and terminating in a semicircular cut-away portion 4. A ridge 5, which is of similar outline as the sides, extends in alignment with the latter.

Having thus fully described my invention, 30 what I claim as new, and desire to secure by Letters Patent, is—

The design for a dust-pan, substantially as herein shown and described.

In testimony whereof I affix my signature 35 in the presence of two witnesses.

HENRIETTA GERWIG.
